(57) **CLAIM**

We claim the ornamental design for a tray for increasing compliance in the administration of a medicament by more than one route, as shown and described.

DESCRIPTION

FIG. 1 is a perspective elevational view of the tray for increasing compliance in the administration of a medicament by more than one route showing our new design;

FIG. 2 is a front elevational view thereof;

FIG. 3 is a back elevational view thereof;

FIG. 4 is a right elevational view thereof;

FIG. 5 is a left elevational view thereof;

FIG. 6 is a top elevational view thereof; and,

FIG. 7 is a bottom elevational view thereof.
